152 INVENTOR:
JOSEPH G. PESSINA,
BY George J. Mager
HIS ATTORNEY

UNITED STATES PATENT OFFICE

2,641,685

FLUORESCENT HAND LAMP CONSTRUCTION

Joseph G. Pessina, St. Louis, Mo., assignor to
Emro Manufacturing Company, Incorporated,
St. Louis, Mo.

Application May 22, 1951, Serial No. 227,555

5 Claims. (Cl. 240—10.65)

1

The present invention relates generally to a novel and improved construction for fluorescent hand lamps.

More particularly, the invention is directed to an improved construction for fluorescent hand lamps of the type which is characterized by being provided with a self-contained source of power, so that immediate illumination is available by the manipulation of a switch.

The demand for this type of lamp is increasing, so much so that lanterns and similar devices are being replaced thereby.

Fluorescent hand lamps are invaluable in emergencies, for example in the case of train wrecks at night, floods, and so on, in fact wherever illumination is requisite, and electrical power is not available. Lamps of this type are also employed in loading merchandise on carriers at night, aboard ship, in mines and so on, as is understood.

The power in this type of lamp is ordinarily supplied by a pair of standard 45 volt B batteries, and one of the principal disadvantages in constructions heretofore, has been the difficulty encountered in battery unloading and re-loading.

The primary object of the present invention is to overcome this and other disadvantages heretofore inherent in these lamps.

The lamp of the present invention provides means whereby the replacement of batteries becomes a simple and quickly accomplished operation. To this end as will appear, the batteries are supported within the lamp casing on a strap member hinged at one end to the lower portion of a skeleton framework which depends from, and is secured at its upper end to, the top cover member for the casing.

The other end of the battery supporting strap member terminates in a resilient latch portion adapted to releasably engage a lower portion of the framework opposite that portion to which the other end of said strap member is hingedly attached.

The skeleton framework as stated, is rigidly attached at its upper end to the cover for the casing, and a handle is provided on said cover, so that the latter and the framework may be lifted as a unit from the casing, as will appear.

With this arrangement, and because of other provisions to appear, replacement of batteries is facilitated. It will also be seen, that all of the wiring and other elements associated with the lighting system are so mounted as to be undisturbed during the removal and insertion of said unit, and the replacement of batteries therein.

2

Other objects of the invention are to provide a waterproof construction; to provide for such weight distribution that the lamp will float with its front, or light diffusing portion above the water level; and to provide easily accessible and manipulative means for turning on the switch to produce almost instantaneous illumination of floodlight proportion.

There are a number of other inherent features 10 and advantages which will be pointed out in the description to follow, reference being had also to the accompanying drawings, wherein is illustrated the preferred embodiment of my invention.

In said drawings:

15 Fig. 1 is a top plan view of a fluorescent hand lamp constructed in accordance with the concepts of the present invention;

Fig. 2 is a view thereof in front elevation;

Fig. 3 is a vertical sectional view, on an enlarged scale, taken approximately on line 3—3 of Fig. 1, with the batteries omitted in the interest of clarity;

Fig. 4 is a horizontal sectional view taken on line 4—4 of Fig. 3;

20 Fig. 5 is a right end elevational view of the casing, and of the insert unit assembly of the invention, the latter being portrayed as it appears when lifted out of the former;

Fig. 6 is a horizontal sectional plan view 25 through the casing, being taken on line 6—6 of Fig. 5;

Fig. 7 is a full scale view partly in section, being taken on line 7—7 of Fig. 5;

Fig. 8 is a rear elevational view of the insert 30 unit assembly per se;

Fig. 9 is a left end elevational view thereof;

Fig. 10 is a fragmentary sectional view, on an enlarged scale, taken on line 10—10 of Fig. 2;

Fig. 11 is a top plan view of the casing as it 40 appears with the insert unit assembly removed;

Fig. 12 is a detail view of one of the two guide strips provided for the slidable reception of the marginal portions of a reflector member included in said assembly;

45 Fig. 13 is a vertical sectional view, on an enlarged scale, taken approximately on line 13—13 of Fig. 1;

Fig. 14 is a vertical sectional view on an enlarged scale, taken on line 14—14 of Fig. 4;

50 Fig. 15 is a similar view taken on line 15—15 of Fig. 4;

Fig. 16 is a fragmentary reproduction of the lower portion of Fig. 8, illustrating the simple manner whereby the batteries may be replaced;

55 and Fig. 17 is a diagrammatical presentation of a

fluorescent lighting system, the included components of which are incorporated in the insert unit assembly aforesaid.

It is noted at the outset, that the invention is not concerned with the fluorescent lighting system as such. That is to say, no claim whatever is made to the conventional system illustrated diagrammatically in Fig. 17. Said view is presented only for the purpose of demonstrating in conjunction with other views, that an important feature of the invention resides in the arrangement whereby a complete lighting system is incorporated in the removable insert unit assembly.

In Figs. 1 through 4, a fluorescent hand lamp constructed in accordance with the teachings of this invention is designated as a whole by numeral 20.

It includes two main and separable assemblies which normally, that is when the lamp is in use, are so to speak telescopically united and rigidly secured together, as will appear.

The first of these main assemblies consists of a housing or casing, open at the top, and generally indicated by numeral 22. This casing is of sturdy construction, preferably of hardened steel, and the substantially rectangular body portion 24 thereof is adapted to withstand considerable abuse without injury thereto.

Included in said body portion are side walls 26, a rear wall 28, and a front wall comprising two segments or horizontally separated panel members 30 all integrally formed, as the drawings clearly illustrate.

Spanning and enclosing the space obtaining between the inner margins of panels 30, is an arcuate lens member 32, molded of heavy translucent plastic material so as to terminate in integral flat marginal portions 34, as seen to best advantage in Figs. 6 and 10.

When lens member 32 is securely maintained in place as will appear, it is manifest that it combines with the panels 30 to form the front wall of casing 22.

The bottom wall of said casing is designated 36, and is provided with an upstanding peripheral flange 38. The top wall is designated 40, and is provided with a depending peripheral flange 42. Obviously, and as the drawings show, the peripheral configurations of both the top and bottom walls, when viewed in plan, correspond to the horizontal cross-sectional configuration of casing 22.

As particularly clear from an inspection of Fig. 11, the major portion of top wall 40 is open, having been removed to provide a generally rectangular opening 44, including a pair of spaced V-shaped notches 46, and a relatively large U-shaped notch 48 formed centrally of said notches 46. The marginal portion 50 of said wall has formed therein, in predetermined spaced relation, a series of threaded vertical apertures 52, and the front portion of depending flange 42 has four spaced horizontal apertures formed therein.

Bottom wall 36 is solid, and flange 38 thereof is likewise provided with four horizontal apertures spaced similarly to those in flange 42.

Welded as the drawings indicate, or otherwise rigidly attached to the upper surface of the bottom wall, are combined guide and retainer clips 54, the purpose of which will appear.

Each of these clips includes a flat base portion 56, and a pair of upstanding wing portions 58, the upper marginal edge portions 60 of the

latter being flared outwardly, as best seen in Fig. 5.

Illustrated per se in Fig. 12, is one of a pair of elongated channel shaped plates 62, which as 5 will appear, serve a dual purpose. One flange portion 64 of each plate is angularly disposed, and the base portion 66 thereof is provided with a plurality of spaced apertures 68 which correspond to a similar series of apertures provided 10 in each panel 30.

The assembled casing 22 is permanently sealed against entry of moisture by the provision of a rubber gasket 70 along each panel 30; a gasket 72 interposed between bottom flange 38 and the 15 lower end of lens member 32; a gasket 74 interposed between upper flange 42 and the upper end of said lens member; a line of solder or welding, as indicated at 76 in Fig. 3 only, extending from edge 78 of one panel 30 peripherally around the casing to edge 78 of the other panel 30, and along the top edge of flange 38; and a similar seal as indicated at 80 in Fig. 3 only, with respect to flange 42.

As Fig. 3 illustrates, lens member 32 extends 25 from top wall 40 to bottom wall 36 of the casing. This is likewise true of gaskets 70 and channel plates 62. Bolts 82, each passing through aligned holes in a panel 30, gasket 70, marginal portion 34 of lens 32, and through one of the apertures 30 in a channel 62, have nuts 84 applied to the threaded ends thereof.

As viewed in Fig. 2, the uppermost and the lowermost bolts 82 also pass through apertures in top and bottom flanges 42 and 38 respectively.

Thus, as should be clear from an inspection 35 of Fig. 10, a seal is provided along panel portions 30 from top to bottom, while at the same time, lens member 32 is rigidly maintained in position.

At the bottom, as Figs. 3, 4 and 6 demonstrate, 40 lens member 32 is further secured, and a seal is provided, by means of an arcuate plate 86, bolts 88, nuts 90, and gasket 72, as is understood. A similar arrangement is provided at the top, and like parts which appear in the drawings, are identified by the same numerals.

The open top 40 of the casing is normally sealed by a cover member included in the insert unit assembly of the invention, which comprises the second of said main assemblies, and is generally indicated by numeral 100.

Included in assembly 100 is said cover member designated 102; an upwardly extending handle 104 riveted as at 106, or otherwise rigidly secured to said cover centrally thereof; a skeleton framework generally designated 108 which depends from, and is rigidly secured to, said cover member; a latching mechanism generally designated 110 for releasably supporting a pair of standard B batteries within said skeleton framework; an arcuate reflector 112; means for mounting and supporting all of the wiring and other elements shown diagrammatically in Fig. 17, and included in a conventional fluorescent light system; and means for effecting a seal between the cover 102, and the switch and the switch operating knob which are included in said lighting system.

Viewed in plan, the configuration of cover 102 is similar to that of top wall 40. Its peripheral edge 114 is turned downwardly, so as to define between said edge and an endless depressed groove 116, a shallow channel 118 extending entirely around the margin of the cover, as shown.

As best seen in Fig. 7, a rubber gasket 120

is disposed in said channel, and said gasket and cover member are provided with a series of spaced aligned apertures 122 and 123 respectively, which register with the threaded apertures 52 of top wall 40.

When the assembly 100 is in position, screws 124 passing through said apertures and engaging in apertures 52, firmly seat the gasket 120 against wall 40, rigidly secure the cover in place, and thus effectively seal the opening 44.

As shown in the drawings, framework 108 includes four corner angle bars 126, each welded or otherwise rigidly secured at its upper end to a rectangular support 128. This support consists of four angle members 130, mitered and welded together at the corners, with their horizontal flange portions welded to the underside of the cover member 102.

With this arrangement, it should be clear that said framework and said cover form a rigid unitary assembly, which following extraction of screws 124, may be lifted from casing 22 by means of handle 104, as portrayed especially in Fig. 5.

In Figs. 3, 5 and 9, it is seen that the framework also includes two horizontally disposed angle members 132, each of which has its ends welded or otherwise rigidly secured to a pair of said angle bars 126. The angles 132 are disposed at a predetermined elevation, being so spaced relative to latching mechanism 110, that a pair of standard B batteries in superposed relation, may be positioned between said mechanism and said angles.

As appears most clearly in Figs. 4, 5, 8 and 9, the lower ends of angle bars 126 are encompassed by a rectangular metal band 134, welded or otherwise rigidly attached thereto.

The latching mechanism 110 includes a metal strap 136, one end of which is riveted as at 138, to a hinge 140, the latter in turn being riveted as at 142, to a portion of said band 134, as particularly illustrated in Fig. 14.

The opposite end of strap 136 is bent normal thereto, whereby to form a semi-rigid or resilient upward extension 144, which as Fig. 15 in particular illustrates, is adapted in the latched position to bear against an adjacent portion of band 134, and terminates in a laterally projecting substantially V-shaped thumbpiece portion 146, adapted to snap over the upper edge 148 of band 134.

As previously stated, this invention makes no claim whatever to any particular system whereby either intermittent or continuous illumination in this type of lamp may be produced. The system diagrammatically portrayed in Fig. 17 is a standard one, but it is a feature of the present invention that all of the included elements are mounted and supported in the assembly 100, so as to be removable therewith en masse from casing 22.

With this in mind, only the principal elements of the Fig. 17 diagram will be specifically designated, it being taken for granted that an inspection of Figs. 3 through 5, and 7 through 9, will abundantly demonstrate the disposition of the included wiring.

Thus in numerical order, 150 indicates a first or upper battery; 152 a second or lower battery; 154 a socket for the upper and 156 a socket for the lower battery; 158 a plug for insertion into and removal from socket 154; 160 a plug for insertion into and removal from socket 156; 162 a fluorescent tube; 164 the upper, and 166 the lower socket therefor; 168 a terminal plate

assembly; 170 a resistor device; 172 a ballast assembly; 174 a switch; and 176 a knob, partial rotation of which in a clockwise direction will turn on said switch, and similar rotation of which in a counterclockwise direction will turn it off.

The manner in which the conventional socket members 164 and 166 are supported will now be described with particular reference to Figs. 2, 3, 4 and 7. The supporting structures for each 10 socket member are similar, so that the same reference characters are applied to the corresponding upper and lower elements included.

It is noted first of all, that arcuate reflector 112 is rigidly secured to framework 128 in any 15 suitable manner. Preferably as shown, screws 178 passing through the upper and lower portions of said reflector and into engagement with threaded apertures provided in front angle 130 and front segment of band 134, form the attaching 20 means. Hollow spacer elements 180 may be interposed about the screws as shown.

Adjacent the upper and lower ends thereof, portions of reflector 112 are extended forwardly to form angular brackets 182, the body portion 25 being slotted as at 184 for this purpose.

Numerals 186 indicate angular hangers secured by screws 188 to said brackets as shown, and each of said hangers rigidly supports one 30 of said socket members.

The upper and lower brackets 182, and the hangers 186 attached thereto, are cut out or notched as shown, to accommodate passage therethrough of the wires leading from the 35 sockets to other elements of the lighting system.

From the foregoing, it should be apparent that a rigid mounting for tube 162 is provided, so that removal and insertion thereof is an easy matter.

The manner in which terminal plate assembly 40 168 is attached to the upper ends of a pair of corner angles 126, is seen to best advantage in Figs. 3, 7 and 9. There it is seen that said assembly is clamped between two jaws 190 integrally formed with a strap member 192, the ends of which are secured by screws 194 to the left end pair of corner angle bars 126, immediately below the left end angle member 130.

Resistor 170 is supported from assembly 168, as Fig. 7 clearly shows, and ballast assembly 172 is supported in a U-shaped bracket 196 welded, or riveted as at 198, to the underside of cover 102.

Switch 174 is conventional, and includes a housing 200, an upwardly extending hollow threaded portion 202, and a stem 204 projecting 55 beyond the latter.

The invention provides means for mounting this assembly on the cover 102 in a manner to effectively seal the parts. Interposed about portion 202, between the underside of said cover and the upper face of housing 200, is a rubber gasket 206, as illustrated in Fig. 13. A similar gasket 208 is interposed about portion 202, between the upper surface of said cover and the lower end of a hollow nut 210. The latter is formed so as to contain a rubber O-ring 212 which embraces the stem 204.

It should be manifest that tightening of nut 210 not only secures switch housing 200 firmly in place, but at the same time, compresses gaskets 206 and 208 to effectively seal the opening 214 in cover 102. It should likewise be manifest that O-ring 212 seals the opening in nut 210, through which stem 204 projects.

Numeral 216 designates a setscrew by means

of which knob 176 is attached to stem 204. Preferably the body of said knob has formed therein an annular recess 218 into which nut 210 projects, thus shielding the latter against fortuitous displacement.

Reverting now to the channel members 62, and with particular reference to Figs. 4, 6 and 10, it is noted that angular flanges 64 form with the marginal portions 34 of lens 32, a pair of V-shaped vertical slideways 220, along which the side edges of reflector plate ride when the insert unit assembly 100 is raised or lowered.

In use, the assembled lamp of Figs. 1 and 2 is adapted to bring illumination with ease to any selected area or point. Handle 104 facilitates portability, and reflector 112, coated with diffused aluminum, projects the light over a wide spread. Handle 104 also serves to hang the lamp on a hook or other stationary projection, and obviously, the lamp may be employed lying on its side, or supported in an upright position, and so on.

With the insert unit assembly 100 in place, all of the interior elements of the lamp are sealed, as has been explained in detail. The provision of retainer clips 54, the resilient wing portions 58 of which engage band 134 at the corners thereof, eliminates any tendency of the depending portion of said framework to rattle, even with rough handling, as is understood.

Switch control knob 176 is most conveniently located for quick manipulation, particularly in cases where intermittent illumination is desired.

As hereinbefore indicated, an outstanding feature of the invention resides in the assembly 100, which may be lifted from the casing for quick tube renewal or battery replacement. For this purpose, it is only necessary to remove the screws 124, and then raise the entire assembly by means of handle 104.

Tube replacement may thus be easily accomplished, with the assembly 100 in either upright or prone position.

Replacement of the batteries, which are supported on strap 136, is likewise a simple matter, as an inspection of Figs. 8 and 9, together with Figs. 15 and 16 should clarify.

In other words, as assembly 100 is suspended with one hand a short distance above a table or like surface, plugs 158 and 160 are withdrawn from sockets 154 and 156 with the other hand.

Thereupon, application of slight inward pressure to thumbpiece 146 will cause resilient extension 144 to move inwardly from its latched or full line position of Fig. 15, to its unlatched or broken line position.

Immediately following this operation, the combined weight of batteries 150 and 152 will automatically cause strap 136 to swing downwardly about hinge 140, and permit the batteries to slide out of framework 108, as Fig. 16 amply illustrates.

Thereupon, the insert unit is inverted; new batteries are dropped into place, the first battery coming to rest against angle members 132, and the second battery against the first; strap 136 is swung into latching position; a slight blow is struck against the free end of said strap whereby V-shaped thumbpiece 146 snaps over the upper edge 148 of band 134; plugs 158 and 160 are put in place; handle 104 is grasped; the complete assembly is lowered into casing 22, as Fig. 5 also serves to illustrate; and screws 124 are replaced whereby to complete the operation.

It is understood of course, that it is not abso-

lutely necessary to invert the assembly in order to replace the batteries, but this method is a simple one.

With reference to Fig. 11, it is noted that notch 48 is of a size to accommodate passage therethrough of tube 162 and its supporting sockets 164 and 166. Also, that notches 46 facilitate entry of the side marginal edges of reflector 112 into slideways 220, and that the outwardly flared portions 60 of wings 58 serve to guide lower band portion 134 of framework 108 into position when the assembly 100 is inserted.

From the foregoing, it should be apparent that the invention provides a construction which includes many features and advantages not heretofore found in this type of lamp.

Obviously, the construction may be modified in some respects without departing from the spirit of the invention, which is characterized by the provision of a sealed casing or container wherein is supported an assembly, insertable into and removable from the casing as a unit, said assembly incorporating an arcuate reflector; means for supporting all of the elements and wiring included in a conventional fluorescent lighting system; means for facilitating the removal and replacement of either the fluorescent tube or the batteries included in said system; and means for stabilizing the lower end portion of said assembly.

What I claim is:

1. In a fluorescent hand lamp construction: a substantially rectangular casing provided with an arcuate lens in the front wall and a generally rectangular opening in the top wall thereof; a cover plate for normally sealing said opening; a skeleton framework depending from and rigidly secured at its upper end to the underside of the cover plate; a latching mechanism hingedly mounted on the lower end portion of the framework for releasably supporting a pair of superposed B batteries within said framework; spaced retainer clips mounted on the bottom wall of the casing for engaging the free lower corner portions of said depending framework; an arcuate reflector vertically coextensive with and supported by the framework in spaced relation to said lens member; a fluorescent tube disposed between the reflector and said lens also supported by said framework; a switch and an assembly of wiring and related elements forming in combination with said tube and said batteries a conventional fluorescent lighting system mounted in said framework between the uppermost B battery and said cover plate; an actuating stem for the switch projecting upwardly through the cover plate; a manually rotatable knob rigidly secured to the projecting end of said stem; and a handle rigid with said cover plate for lifting from the casing the unitary assembly comprising said framework, said cover plate, and all of the elements supported thereby, and for inserting said assembly into said casing.

2. In a fluorescent hand lamp construction: a substantially rectangular casing provided with an arcuate lens in the front wall and a generally rectangular opening in the top wall thereof; a cover plate removably secured to the top wall of said casing; an endless shallow channel in said cover plate formed by a downwardly turned peripheral edge thereon in conjunction with an endless depressed groove formed therein in inwardly spaced relation to said edge; a compressible gasket disposed in said channel for sealing the opening in said top wall when the cover plate

is in normal position; a skeleton framework depending from and rigidly secured at its upper end to the underside of the cover plate; a latching mechanism hingedly mounted on the lower end portion of the framework for releasably supporting a pair of superposed B batteries within said framework; spaced retainer clips mounted on the bottom wall of the casing for engaging the free lower corner portions of said depending framework; an arcuate reflector vertically coextensive with and supported by the framework in spaced relation to said lens member; a fluorescent tube disposed between the reflector and said lens also supported by said framework; a switch and an assembly of wiring and related elements forming in combination with said tube and said batteries a conventional fluorescent lighting system mounted in said framework between the uppermost B battery and said cover plate; an actuating stem for the switch projecting upwardly through the cover plate; a manually rotatable knob rigidly secured to the projecting end of said stem; a handle rigid with said cover plate for lifting from the casing the unitary assembly comprising said framework, said cover plate, and all of the elements supported thereby, and for inserting said assembly into said casing; and spaced vertical slideways provided on the front wall of said casing for the side marginal edges of said arcuate reflector.

3. In a fluorescent hand lamp construction, the structure set forth in claim 2 wherein the included skeleton framework depending from the cover plate comprises: four corner angle bars each rigidly secured at its upper end to a rectangular support consisting of four angle members mitered and welded together at the corners, the horizontal flange portions of said angle members being rigidly secured to the underside of said cover member; a pair of horizontally disposed angle members each of which has its ends rigidly secured to a pair of said corner angle bars in such spaced relation relative to said latching mechanism as to snugly confine said pair of superposed B batteries therebetween; and a rectangular metal band encompassing the lower ends of said corner angles and rigidly secured thereto.

4. In a fluorescent hand lamp construction, the structure set forth in claim 2 wherein the latching mechanism for releasably supporting the pair of superposed B batteries comprises:

a rectangular band member surrounding and rigidly secured to the lower end portions of said skeleton framework; a metallic strap member; a hinge element connecting one end of said strap to a portion of said band member; a semi-rigid upwardly projecting extension integral with the other end of said strap adapted in the latched position of said mechanism to bear against an adjacent portion of said rectangular band; and a laterally projecting V-shaped thumbpiece portion on said extension adapted to snap over the upper edge of said band member whereby to releasably maintain said strap in latched and battery supporting position.

5. In a fluorescent hand lamp construction, the structure set forth in claim 2 wherein the recited switch of the said conventional fluorescent lighting system includes a housing, an upwardly extending hollow threaded portion and a stem projecting beyond the latter, and wherein said rotatable knob for actuating the switch is secured to the projecting stem thereof by a setscrew, and means for sealing said cover plate about said elements, said means comprising: a resilient gasket interposed about the hollow threaded portion of said switch between the bottom face of said cover and the upper surface of said housing; a hollow nut in engagement with the upper end of said threaded portion; a resilient gasket interposed about said threaded portion between the top face of the cover plate and the bottom surface of said nut; an O-ring of resilient material seated in the upper portion of said nut about said stem; and an annular recess formed in said knob for shielding said nut against fortuitous displacement thereof.
